UNITED STATES PATENT OFFICE.

CHARLES HEIM AND STEPÁN JELLENIK, OF NORTH TONAWANDA, NEW YORK.

RAIL-JOINT.

1,079,551.

Specification of Letters Patent. Patented Nov. 25, 1913.

Application filed May 17, 1912. Serial No. 697,909.

To all whom it may concern:

Be it known that we, CHARLES HEIM, a citizen of the United States, and STEPÁN JELLENIK, a subject of the King of Hungary, both residents of North Tonawanda, in the county of Niagara and State of New York, have invented certain new and useful Improvements in Rail-Joints; and we do hereby declare the following to be a full, clear, 10 and exact description of the invention, such as will enable others skilled in the art to which it appertains to make and use the same.

Our invention relates to rail-joints, and 15 more particularly to that class wherein nuts and bolts are dispensed with.

One of the objects of our invention is the provision of simple and durable means for protecting the meeting ends of two rail-sections and retaining them in line with each other so that car-wheels can pass from one rail section onto another without the usual pounding or hammering, thus minimizing the tendency of parts becoming 25 loose and contributing to the smooth and even running of trains.

Another object is the provision of an improved joint which will enable the laying of a greater number of feet of trackage within 30 a given time and which will greatly reduce the maintenance cost.

A further object is the provision of improved and simple means for securing the rail sections in place.

With these and other objects to appear hereinafter, the invention consists in the construction and arrangement of the several parts, which will be more fully hereinafter described and claimed.

In the drawings,—Figure 1 is a perspective view of portions of two rail-sections or lengths joined by means of our improved rail-joint. Fig. 2 is an enlarged cross section of a rail and our rail-joint. Fig. 3 is a vertical section taken on line 3—3, Fig. 2. Fig. 4 is a vertical section taken on line 4—4, Fig. 2. Fig. 5 is a vertical section taken on line 5—5, Fig. 2. Fig. 6 is a detached perspective view of one of the lock-pins for locking the rail-sections within the chair of the joint. Fig. 7 is a perspective view of a representative form of key, such as must be used to remove the lock-pins from the joint.

Referring now to the drawings in detail, similar letters of reference refer to similar parts in the several figures of the drawing.

The reference letter A designates the rail comprising sections or rail-lengths *a* which are supported in the usual manner on ties B, 60 shown in dotted lines in Fig. 2. Where the sections or rail-lengths meet, they are secured in rail-chairs C secured to ties. The rail is of the usual construction having the tread portion D, the base or flange portion 65 E, and the web F connecting the tread and base or flange.

The rail-chair is cast in one integral piece and comprises a base portion G, flanges H spaced from said base portion G but connected therewith at their outer edges, as at *h*, and integral fish-plates or side members I spaced apart so that a substantially inverted T-shaped opening is formed in the chair in which the base portion and a portion of the 75 web of adjacent ends of two rail sections are placed. In order to facilitate the ready placement of the rail-lengths into the chair or space between the fish-plates, said opening in the main is somewhat wider than the 80 webs of the rail sections, except at its upper part where the fish-plates have inwardly-projecting contact portions *i* which bear against opposite faces of said webs.

At two or more points in the length of the 85 rail-chair, alined openings J are pierced and in line with each pair of said openings, an opening K is provided in the web of each rail-section. The openings in one of the 90 fish-plates and in the webs of the rail-sections are of equal diameter and the opening in the other fish-plate is shouldered to provide an abutment L and a key opening M.

A lock-pin N is provided which enters the alined openings, and has one end in 95 contact with the abutment L. In order to prevent the lock-pin becoming accidentally disengaged by the jarring to which the rail is subjected, inwardly-projecting studs O are provided in the openings of each fish-plate. The lock-pin has a circumferential 100 groove P near each end and a longitudinal groove extending from one of said grooves P to the distant or first-inserted end of the pin, intersecting the circumferential groove at 105 said end.

The studs O in the openings of the fish-plates are arranged in line so that when the lock-pin is inserted, said studs enter the longitudinal groove *p* thereof, and when the 110 first-inserted end of the lock-pin comes in contact with the abutment L, said studs are in line with the circumferential grooves P of said pin. Now upon insertion of a prop-

erly formed key into the key opening M, the lock-pin can be turned so that the longitudinal groove *p* is moved out of registration with the studs O, thus preventing lengthwise movement of the pin and as the studs are made of a size to snugly fit the circumferential grooves P, considerable force is required to turn the pin with reference to the studs, owing to the latter having frictional contact with opposite walls of said circumferential grooves. Assurance is therefore had that the rails will be properly locked within the rail chair.

The key is designated by the letter R and is adapted to enter a socket S formed in the first-inserted end of the lock-pin, said socket having its wall provided with one or more ribs or projections *s*, and the key having a similar number of longitudinal grooves *r* into which the ribs or projections *s* are adapted to fit when the key is inserted in the key opening M and enters the socket S. In order that the lock-pin may not be turned by maliciously inclined persons, each key-opening is provided with inwardly-projecting studs T adapted to fit the grooves *r* in the key and enter a circumferential groove *t* in said key at the inner ends of the longitudinal grooves *r*.

30 The key opening as described is merely representative of a type of keys that will safe-guard the lock-pin against being turned and any special key which will serve the purpose may be used in lieu of that shown.

35 The rail chair is secured in place by means of spikes U, shown in dotted lines in Fig. 2, and in order that lengthwise movement of the rail chair is guarded against the longitudinal edges of the flange portions of the chair are notched, as at *u*, into which the spikes U fit.

40 By forming the rail-chair in one integral piece and confining the adjacent ends of the rail-lengths therein, a solid bearing is provided for the rail; and owing to the upward and downward movement of the rail being prevented within said rail-chair, also all lateral movement, all pounding or hammering is eliminated. This greatly minimizes 45 the tendency of the parts to become loose and also provides a rail-joint which will assure the smooth and easy running of cars thereover.

Having thus described our invention, what 50 we claim is:

1. The combination with a rail having a transverse opening in its web, of a rail-chair having an inverted T-shaped opening therein, said rail-chair having integral fish- 55 plates lying on opposite sides of the web of said rail, said fish-plates having openings alined with the opening in said rail, at least one of said openings in the fish-plates hav-

ing an inwardly projecting stud, and a lock-pin having a longitudinal groove adapted 65 to pass over said stud when entering the pin in said openings and a circumferential groove at one end of said longitudinal groove to receive said stud when turning the lock-pin, said stud and circumferential 70 groove serving to prevent dislodgment of said lock-pin.

2. The combination with a rail having a transverse opening in its web, of a rail-chair having fish-plates arranged on opposite 75 sides of the web of said rail and provided with openings in line with the opening in said rail, the openings in said fish-plates having inwardly-projecting studs, and a lock-pin fitting into said openings and 80 having a circumferential groove near each end and a longitudinal groove extending from the first-inserted end to the circumferential groove near the other end thereof, said longitudinal groove permitting the 85 entrance of the pin into said openings and said circumferential grooves receiving the studs in the openings of said fish-plates when turning said pin to prevent accidental dislodgment of the latter.

3. The combination with a rail, of a rail-chair having opposite fish-plates between which adjacent sections of said rail are located, each section of the rail having a transverse opening and said fish-plates having 95 openings in line with the openings of said rail-sections, the openings in said fish-plates having inwardly-projecting studs and the opening in one fish-plate being reduced in diameter to form a key-opening and having 100 an inwardly-extending rib or projection, a lock-pin for each set of alined openings having a circumferential groove near each end and a longitudinal groove extending from the first-inserted end of said pin to the circumferential groove near the other end thereof, said lock-pin having also a socket 105 in said first-inserted end provided with inwardly projecting ribs, and a key for turning said lock-pin having a circumferential 110 groove near one end and longitudinal grooves extending from said circumferential groove to said end of the key, said longitudinal grooves passing over the ribs in the socket of said lock-pin and over the projection in said key opening and said circumferential groove being adapted to receive 115 the projection in said key opening.

In testimony whereof, we have affixed our signatures in the presence of two subscribing 120 witnesses.
